UNITED STATES PATENT OFFICE.

ALBERT B. WILSON, OF LOWELL, MASSACHUSETTS.

MOISTENING DEVICE.

1,240,279.

Specification of Letters Patent. Patented Sept. 18, 1917.

Application filed March 27, 1916. Serial No. 86,983.

To all whom it may concern:

Be it known that I, ALBERT B. WILSON, a citizen of the United States, residing at Lowell, in the county of Middlesex and 5 State of Massachusetts, have invented certain new and useful Improvements in Moistening Devices, of which the following is a specification.

This invention belongs to the class of 10 moistening devices which are used especially by cashiers and others who have occasion to count money or to count and handle any other sheet material such as paper. It may also be used by persons who have occasion 15 to handle sheet material of any kind.

Its purpose is to provide a convenient device whereby the fingers, thumbs, or fingers and thumb may be moistened more or less to prevent slipping and to secure a more 20 certain touch in handling such materials.

It is so made that more or less moisture can be taken up as desired.

It may be instantly taken apart for cleaning and instantly put together again, while 25 the dirt is carried over or down and settles in a water container in such a position that it is not stirred up or disturbed by the continued use of the device.

It includes substantially a water container, preferably of rectangular form, open 30 at the top and having supports or bearings for a removable shaft which may or may not be revolvable, together with one or more disks of firm absorbent material, preferably 35 having a fine grain and of hard texture, such as, for instance, compressed felt of pure wool. I may use one or more disks removably and revolvably mounted on the shaft, of such size and of such position that they will 40 project above the top rim of the water container and will extend below the water level therein.

The material should be of such texture 45 that capillary attraction will cause the water to work upward and keep the top of the disks moist at all times.

The top surface, however, of the disks will 50 not be too moist, and if more moisture is desired, disks can be readily swung around by the thumb or finger to carry up more water.

Any excess rapidly runs down through the disk material or between the disks, and my guard member prevents splashing.

The material is of such close grain texture 55 that dirt does not readily stick to it, but

runs down with the water or is carried over when the disks are caused to crawl or spin.

I prefer also to provide a guard of sheet material having ends bent downwardly and outwardly to rest upon the bottom of the 60 container and having sufficient spring to engage the ends of the container, such guard having also an opening in the top through which disks project. I also prefer to provide the guard with ears, preferably of 65 semi-circular form, stamped from the material of the guard, which project upward on each side of the disks to assist in keeping them in place and to act as brakes to prevent spinning.

I prefer also to provide a detachable guide member of sheet material, having legs which straddle the shaft and rest upon the bottom of the container, and which extends upward and over the disks proximate the top thereof, whereby the device can be used for moistening the flaps of envelops, stamps, etc.

In the drawings, Figure 1 is a perspective view of the device assembled, the detachable guide member being indicated by dotted 80 lines. Fig. 2 is a side sectional elevation with the parts in place. Fig. 3 is a sectional side elevation of the water container. Fig. 4 shows the guard, shaft, and one of the disks in perspective and disassembled. Fig. 85 5 is an end view with part of the tank broken away showing the detachable guide member in place, and Fig. 6 is a side elevation of the guide member detached.

A represents the water container which 90 is shown as being in the form of a tank, with a bottom 10, ends 11 and 12, sides 13 and 14, and with an open top. At each side is a ridge, such as shown at 15, in which I prefer to make a semi-circular depression 16 95 which serves as a support or bearing for one end of a shaft 20.

Upon this shaft I mount one or more disks 30, 31, 32 which are preferably made of hard, fine grained compressed felt of 100 pure wool. I might use a single disk, but I prefer to use a plurality. The shaft and its support are so placed, and the disks are of such diameter, that the disks project above the top edge of the water container and extend down into it below the water level, which is indicated at 33 by the dotted line.

The guard member indicated by B is preferably stamped from a single piece of sheet material, such as brass or aluminum, and 110

includes a flat top 40 in which is an opening 41 of a size to permit the disks to project through with a fairly close fit when the ends 42 and 43 which are bent down and out rest 5 upon the bottom of container A. The ends or legs 42 and 43 should be of such length that the top 40 of the guard member will be substantially below the top of the water container, and I prefer that the ends and sides 10 around the top on the inside should be slightly beveled, as shown, whereby any water which may get on the top 40 will run back where it belongs and will not run over on the outside of the tank. Semi-circular 15 ears 44 and 45 are stamped from the material and bent upwardly as shown. The ends 42 and 43 serve as legs, and preferably are bent outward so as to normally be a slightly greater distance apart at their free ends 20 than the bottom inside length of container A, whereby the guide will not rattle and cannot be readily shaken out. This top 40 of the guard member B should just fit in the top of container A so that there will be no 25 chance for water to stand between its bent down ends 42 and 43 and the ends 11 and 12 of the water container A.

In Figs. 5 and 6, I show a device, which I will call a detachable guide member, C, 30 which is preferably stamped from a single piece of sheet material so as to have legs 50 and 51, the space between being of such width and height that they can straddle the shaft 20 and rest upon the bottom of the 35 container. I prefer to bend up a tongue from the material 52, which is cut out, so as to press the device between an ear 45 and the adjoining disk, whereby the guide is held in place without rattling. The other 40 end of the guide extends upward and is bent over at 53, proximate the top of the disks, and is preferably turned up at the extreme corners 54 and 55 to facilitate the introduction of the flap of an envelop or similar 45 article.

To use for this purpose, the flap with the gummed side down is drawn between guide C and the top of the disks, preferably with the thumb of one hand pressed down upon 50 the top 53 of the guide so as to insure thorough contact.

If the disks become worn, loose or wabbly, the ears 44, 45 may be bent against them to keep them steady.

55 I can use my disks of hard, fine grained, compressed felt of pure wool without a shaft or guard, allowing them merely to rest on the bottom of the water container where they serve as a very satisfactory absorbent 60 medium whether they are revoluble or stationary.

I claim:

1. In a moistening device, the combination of a water container having interior 65 shaft supports near the top at each side, a

shaft which is removably mounted in such supports, and one or more disks of absorbent material so revolubly mounted on the shaft as to project above the top rim of the water container and to extend below the 70 water level therein, combined with a removable guard of sheet material having ends bent downwardly and outwardly to rest upon the bottom of the container and to engage the ends thereof, such ends being of 75 such length that the top of the guard will be below the top rim of the water container, and will fit closely inside thereof at a point above the water level, and having an opening in the top through which the disks project. 80

2. In a moistening device, the combination of a water container having interior shaft supports near the top at each side, a shaft which is removably mounted on such supports, and one or more disks, each formed 85 entirely of compressed felt, so revolubly mounted on the shaft as to project above the top rim of the water container and to extend below the water level therein, combined with a removable guard of sheet 90 material having ends bent downwardly and outwardly to rest upon the bottom of the container and to engage the ends thereof, such ends being of such length that the top of the guard will be below the top rim of the 95 water container and having an opening in the top through which the disks project.

3. In a moistening device, the combination of a water container having interior shaft supports near the top at each side, a shaft 100 which is removably mounted on such supports, and one or more disks, each formed entirely of compressed felt, so revolubly mounted on the shaft as to project above the top rim of the water container and to extend 105 below the water level therein, combined with a removable guard of sheet material having ends bent downwardly and outwardly to rest upon the bottom of the container and to engage the ends thereof, such ends being of 110 such length that the top of the guard will be below the top rim of the water container, and such top being of a size to fit closely therein, an opening in the top through which the disks project, and ears which project 115 upwardly proximate the sides of the disks.

4. In a moistening device, the combination of a water container having interior shaft supports near the top at each side, a shaft 120 which is removably mounted on such supports, and one or more disks, each formed entirely of compressed felt, so revolubly mounted on the shaft as to project above the top rim of the water container and to extend 125 below the water level therein, combined with a removable guard of sheet material having ends bent downwardly and outwardly to rest upon the bottom of the container and to engage the ends thereof, and an opening in the top through which the disks project, 130

together with a detachable guide member of sheet material having legs which straddle the shaft and rest on the bottom of the container, and which extends upward and over 5 the disks and proximate the top thereof.

5. In a moistening device, the combination of a water container having interior shaft supports near the top at each side, a shaft which is removably mounted on such supports, and one or more disks, each formed entirely of compressed felt, so revolvably mounted on the shaft as to project above the top rim of the water container and to extend below the water level therein, combined with 10 a removable guard of sheet material having ends bent downwardly and outwardly to rest upon the bottom of the container and to engage the ends thereof, an opening in the top through which the disks project, and 15 ears which project upwardly proximate the sides of the disks, together with a detachable guide member of sheet material, having legs which straddle the shaft and rest on the bottom of the container, a tongue adapted to 20 engage an ear, and a part which extends upward and over the disks and proximate the 25

top thereof having its corners turned up above the disk.

6. In a moistening device, the combination of a water container having interior shaft supports near the top at each side, a shaft which is removably mounted on such supports, and one or more disks, each formed entirely of compressed felt, so revolvably mounted on the shaft as to project above the top rim 30 of the water container and to extend below the water level therein, combined with a removable guard of sheet material, having a top which fits closely in the top of the water container, and ends bent downwardly and 35 outwardly to rest upon the bottom of the container and to engage the ends thereof, such ends being of such length that the top of the guard will be below the top rim of the water container, an opening in the top 40 through which the disks project, and ears which project upwardly and engage the 45 sides of the disks.

In testimony whereof I hereto affix my signature.

ALBERT B. WILSON.
